GREASE GUN

William L. Ostendorf, Rayland, Ohio

Application July 29, 1938, Serial No. 221,985

14 Claims. (Cl. 221—47.3)

My invention relates to lubricant guns particularly to guns known as booster guns, and more particularly to guns that operate on the principles of a pneumatic hammer. The invention consists in certain refinements and improvements in structure, by virtue of which more efficient operation is realized.

An exemplary embodiment of the invention is illustrated in the accompanying drawing, in which the gun is shown partly in axial section and partly in side elevation.

The structure in which the invention is found includes a pistol-shaped body including a barrel B and a handle H. The bore of the barrel B provides a cylinder 20 to which lubricant is delivered (usually under superatmospheric pressure) from a supply, and in such cylinder a ram 19 is reciprocable for forcing the lubricant under augmented pressure to the parts to be lubricated. The muzzle of the gun includes a threaded socket S, through which the lubricant cylinder 20 opens, and by means of which the cylinder is connected to a fitting or a conduit leading to the ultimate point of lubricant delivery. In this case, the supply of lubricant is held, above a piston P, in a container C; the container is carried in rigid though removable assembly with the gun; and the piston is backed by a compressed helical spring D that maintains the store of lubricant under pressure. A port E provides communication between the container and the ram-cylinder 20.

The ram is powerfully reciprocated in the cylinder 20 between the position shown, in which the port E is open to the flow of lubricant from the container into the cylinder, and a position in which the port E is closed, and lubricant is ejected from the cylinder, it being understood that, in the initial movement of the ram from the position first mentioned, the body of the ram, advancing against the charge of lubricant received from the supply, closes the port.

The means for reciprocating the ram are included in a power cylinder 11 arranged in axial alignment with lubricant cylinder 20. The ram extends into the power cylinder, and is equipped with an impact-sustaining head 30. The ram carries at an interval from such head a piston 35 that engages the wall of the power cylinder in snug, sliding engagement. Beyond the head 30 of the ram, the power cylinder includes a plunger-hammer 14. The body of the gun includes a system of ports and passages communicating with a supply of compressed air, and, subject to the control of valves 1, 6 and 21, presently

to be described, these passages deliver compressed air to the power cylinder in such manner that the following operations are effected:

When the reciprocable ram 19 enters the position shown and a charge of lubricant has been delivered into cylinder 20, the plunger 14 is set in rapid oscillation in the power cylinder 11. The oscillating plunger delivers a succession of blows upon the head 30 of the ram, and drives the ram in right-to-left direction through its lubricant-delivering stroke. When the ram reaches the end of such delivery stroke, the oscillation of the plunger 14 is arrested, and the ram is returned to the start of its stroke, uncovering the port E to admit another charge of lubricant to the cylinder 20. These operations are automatic and are automatically repeated over and over again, subject, as will appear, to the will of the user.

To the end that the structure may be readily understood, I shall describe in greater detail the operation of the gun through one complete reciprocation of the ram, and among the several novel and important features of invention which will thus be presented, I call particular attention to two:

First.—To the end that a maximum charge of lubricant, even of the heavier greases, shall be introduced to the cylinder 20, the reciprocating ram is arrested or delayed in port-uncovering position. As an example of means for achieving this desideratum, I show a device for retarding the movement of the ram into port-uncovering position. By utilization of such a device the port may be slowly opened, providing a prolonged interval of time in which the lubricant may flow from container C into cylinder 20.

Second.—The ram 19 operates only against the lubricant in cylinder 20 during its power stroke. There is no other resistance to ram movement, save such resistance as is caused by mechanical friction. Under the drive of the reciprocating hammer element 14, the movement of the ram is progressive from one end of its working stroke to the other, and there is no retrograde motion of the ram, nor recoil from the blows delivered by the hammer element.

The medium for operating the gun is compressed air, but other fluids under pressure may be used, and the term air is of general significance as used in the appended claims.

The handle of the gun includes a passage F which is connected to a supply of compressed air. A stop valve 1, normally closed by a spring, is controlled by a trigger T. In order to effect

operation of the gun, the trigger is pressed and held. In consequence the valve 4 opens and under trigger pressure is retained in open position; compressed air enters a passage 2 and flows to ports 3 and 4; and these ports, under the control of valve 6, are adapted to establish alternate lines of flow from the passage 2. One line of flow delivers air to the right-hand end of power cylinder 11 for reciprocating the hammer element, and the other line delivers air to the left-hand end of such cylinder for returning the ram from the end of its lubricant-delivering stroke to recharging position. More specifically, the valve 6 consists in a cylindrical plunger that is reciprocable in a cylinder 5 between alternate positions of service. The plunger includes an axial passage 33 that permits displacement of air from one end of the cylinder to the other when the plunger is moved between its said alternate positions. The plunger carries a rigid finger 31 that extends upward, through a slot 40, into the power cylinder 11; as will presently appear, the upper tip of the finger is alternately engaged by head 30 and piston 35 of the reciprocating ram, and in consequence the finger is intermittently shifted first in one direction and then in the other, carrying the plunger valve 6 between its alternate positions of service in cylinder 5; the lower end of the finger 31 extends a slight but sufficient interval below the plunger 6 and cooperates with a spring-backed detent 36 in yieldingly securing the plunger valve in its alternate positions. The body of the plunger valve includes a circumferential groove 7, and a passage 41.

One of the two lines of flow, alluded to above, is provided by a relatively long passage 9 that establishes communication between a port 8 in the wall of valve-cylinder 5 and a port 10 in the wall of power cylinder 11. The other line of flow is provided by a relatively short passage 32 opening at one end in the valve-cylinder and at opposite end in the power cylinder.

A by-pass 13 of relatively small diameter extends from the passage 9 to the power cylinder, and opens into such cylinder at a point between the piston 35 and the hammer element 14. When the valve 6 is in the position illustrated, its groove 7 establishes communication between port 3 of passage 2 and port 8 of passage 9; the body of the valve to the left of the groove blanks the port 4, and the passage 41 in the body of the valve establishes, with passage 32, communication between the region 11a in the power cylinder on the left of the piston 35 and a passage 42 opening to the outer atmosphere.

Assuming that all parts of the gun are in the positions illustrated when the trigger is pressed, it will be seen that the compressed air entering passage 2 flows through ports 3 and 8 into passage 9. While the outlet port 10 of passage 9 is, as shown, closed by the body of the hammer element 14, air enters the power cylinder, by way of by-pass 13, and forces the hammer element in left-to-right direction; the body of the hammer element is circumferentially recessed between two shoulders 28 and 48, and in such left-to-right movement of the hammer element the shoulder 28 is carried to the right of port 10, with the consequence that air flows from passage 9 into a passage 45, the passage 45 opening into the power cylinder 11 through a port 12. From passage 45, the air flows through aligned ports 16, 17 and 18 into the power cylinder and drives the hammer element forward in its first power stroke,

the leading end of the hammer delivering a powerful blow to the head 30 of the ram. The ram is thus driven forward through the first increment of its working stroke, in which the port E is closed and lubricant delivered under high pressure from cylinder 20.

In such movement of the parts, the shoulder 28 on the hammer element is carried to the left of the ports 10, 12, before the blow is delivered to the ram. That is, communication between the supply of compressed air and the region in the power cylinder to the rear of the hammer element is blanked before the blow is delivered, but it will be understood that the stroke of the hammer element is completed under the expansive forces of the body of compressed air in passage 15 and in cylinder 11 to the rear of the hammer element.

As the hammer element moves forward in blow-delivering direction, the body of air between the piston 35 and the hammer element is compressed to superatmospheric pressure, and under such pressure seeks escape through a port 22 and a passage 24. A pressure relief valve 21 stands in communication with such port and passage, and such relief valve is adapted to open at a critical pressure well below the pressure of the air that drives the hammer element forward, but sufficiently higher than atmospheric value to operate the sleeve-valve 21. More particularly, the sleeve-valve 21 is arranged in an annular or cylindrical slideway 43 in the body of the gun; the sleeve-valve is slotted, and a pin 37, secured in the gun body, extends into such slot and prevents sleeve-valve rotation; the sleeve-valve includes two ports—the port 17 already mentioned, and a port 23; the sleeve valve is reciprocable axially between the position shown, in which port 17 registers with the ports 16 and 18, and a position in which port 23 registers with two passages 25 and 26. When the port 17 is in registry with ports 16 and 18, communication is established between the passage 15 and the power cylinder as shown, and when port 23 is registered with ports 25 and 26 communication is established between the power cylinder and the outer atmosphere.

The passage 24 opens into the forward end of the cylindrical slideway 43, as indicated at 44, and communication is established between the power cylinder 11 and the rear end of the slideway, by means of slots 38 formed in the rear edge of the sleeve-valve 21. As the hammer element approaches the end of its power stroke and delivers a blow to the head 30 of the ram, the pressure of the air compressed between the piston 35 and hammer element approaches maximum value. Such pneumatic pressure, transmitted through passage 24 to the forward end of the slideway 43, effects the movement of the slide-valve 21 into its alternate position, blanking the port 18 and bringing port 23 into registry with ports 25 and 26. Upon registry of the ports 23, 25, 26 the air behind the hammer element is released to the outer atmosphere. Under the influence of the air compressed between the hammer element and piston 35, the hammer element is moved in reverse direction, to the right-hand limit of its right-hand end of the range of reciprocation. This body of compressed air between the hammer element and the piston 35 operates to prevent retrograde movement of the ram in the intervals between the ram-impelling strokes of the hammer element.

In such reverse movement of the hammer element, the ports 10, 12 are opened; the port 25 is

(by the body of the hammer element) closed, and, since the port 17 is then out of registry with ports 16 and 18, an air cushion is formed between the end wall of the power cylinder 11 and the hammer element. This air cushion is of manifest utility in arresting the left-to-right movement of the hammer element suddenly but without violence. Additionally, the pressure of the air in such cushion, transmitted through slots or ports 38 to the right-hand end of slideway 43, effects the return of the slide-valve 21 to its original position—in which position it is here shown. Thus it is that the line of air flow from passage 9 to the port 18 is re-established, and air at supply pressure is again caused to drive the hammer element through its blow-delivering stroke.

In such manner the hammer element is automatically reciprocated, delivering a succession of blows to the head of the ram 19. The hammer blows drive the ram step-by-step through its lubricant-delivering stroke, and it will be noted that the power cylinder is vented on the left of the piston 35, through passages 32, 41, 42, to the outer atmosphere, so that the ram need not and does not operate against a superatmospheric pressure. When the ram approaches the end of its working stroke, its head 30, coming to abutment upon the tip of the rod or finger 31, carries the valve 6 in right-to-left direction into its alternate position. As the valve 6 enters its said alternate position, the ports 3 and 8 are blanked, and communication is established between port 4 and passage 32. Thus, the passage 9 is closed to the supply of compressed air, and the hammer element comes to rest, while air at supply pressure flows from passage 2, through port 4 and passage 32, into the forward end of the power cylinder. Under the pressure of such air on piston 35, the ram moves in left-to-right direction, and returns to the starting point of its working stroke. In such return movement of the ram, the piston 35 engages and shifts the rod 31 in left-to-right direction, thereby restoring the valve 6 to its illustrated position. Thus, as the ram re-enters initial position and the cylinder 20 is recharged with lubricant, communication is re-established between passages 2 and 9, with the consequence that the hammer element is again set in reciprocation, and the ram is again driven through a lubricant-delivering stroke. It will be perceived that so long as the trigger T is pressed inward, the operation described will continue. Alternately, when the trigger is released and the flow of compressed air to passage 2 interrupted, the operation is arrested.

As already mentioned, a valuable feature of the invention resides in structure that prolongs the interval in which the port E remains open to the flow of lubricant from supply container C to cylinder 20, and as has been also mentioned this desideratum is in this case obtained by retarding or delaying the movement of the ram into port-uncovering position, whereby, even though the automatic reciprocation of the ram is continuous (or substantially so), the practical effect gained is the same as that which would be realized if the ram were manually returned to lubricant-admitting position and there held until an adequate charge of lubricant had entered the cylinder 20. In achieving this effect automatically, the effective cross sectional area of the air passage between the forward end 11a of the power cylinder and air-supplying passage 2 is made relatively small, so that the flow of

air into the cylinder is restricted to such value that the ram moves with the desired low velocity into lubricant-admitting position. In this case, I advantageously provide a needle-valve 45 to regulate the effective area of such air passage. By adjustment of such needle-valve, the flow of the ram-operating air into the forward end of the cylinder may be minutely regulated.

When in service the store of lubricant in container C has been exhausted, the container is removed from barrel B and re-charged.

Many variations and modifications of the structure described are permissive within the terms and intent of the appended claims.

I claim as my invention:

1. In a lubricant gun including a ram adapted to deliver from the gun lubricant under high pressure, a pneumatic hammer adapted with repeated blows to drive said ram through its lubricant-delivering stroke, and a passage for hammer-operating air; the improvements herein described that comprise means for returning said ram from the end to the starting point of its lubricant-delivering stroke, said means including

20 a pneumatic cylinder, a piston carried by said ram independently of said hammer and reciprocable in said cylinder, and a valve movable into position to by-pass air from such passage to said cylinder as the ram approaches the end of its said lubricant-delivering stroke.

2. In a lubricant gun including a ram adapted to deliver from the gun lubricant under high pressure, a pneumatic hammer adapted with repeated blows to drive said ram through its lubricant-delivering stroke, and a passage for hammer-operating air; the improvements herein described that comprise means for returning said ram from the end to the starting point of its lubricant-delivering stroke, said means including

30 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

35 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

45 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

50 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

55 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

60 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

65 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

70 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

75 a pneumatic cylinder, a piston carried by said ram independently of said hammer and reciprocable in said cylinder, and a valve movable into position to by-pass air from such passage to said cylinder as the ram approaches the end of its said lubricant-delivering stroke, said means including

der, into which said ram extends comprising an air trap in which the hammer element, moving through a ram-driving stroke, forms an air cushion, said cushion being adapted, after impact of the hammer element with the ram, to return such hammer element to the starting point of such stroke.

5. A lubricant gun including a pneumatic hammer whose hammer element consists in a plunger in a pneumatic cylinder, a lubricant-ejecting ram extending inward into said cylinder, and a system of ports and passages and valves organized with said cylinder for controlling the supply and release of compressed air, to effect the movement of said hammer element against the end of said ram and the travel of the ram in lubricant-ejecting direction, the end of said pneumatic cylinder into which said ram extends comprising an air trap in which the hammer element, moving through a ram-driving stroke, forms an air cushion, one of said valves comprising a valve member movable between alternate positions in a pneumatic valve chamber, one of the passages of said system leading from the air-cushion end of said pneumatic cylinder to said valve chamber, whereby the pressure of the body of air compressed by the hammer element in such cylinder is transmitted to said valve chamber, to effect the movement of said valve member between alternate positions.

6. In apparatus of the class described including a lubricant cylinder having an inlet, a ram for ejecting lubricant from said cylinder, a pneumatic cylinder axially aligned with said ram, a plunger reciprocable in said pneumatic cylinder to drive said ram through its lubricant-ejecting stroke, an inlet passage for delivering compressed air into said pneumatic cylinder to the rear of said plunger to impell the plunger against said ram, an outlet passage for releasing air from said pneumatic cylinder to the rear of said plunger, and a valve movable between a position in which said inlet passage communicates with said cylinder and said outlet passage is blanked, and a position in which said outlet passage communicates with said cylinder and said inlet passage is blanked, and a passage leading from said pneumatic cylinder (to the fore of said plunger) to said valve, whereby air compressed by the plunger moving in said cylinder into ram-driving position is supplied to said valve for effecting movement of the valve from one to the other of its alternate positions.

7. In apparatus of the class described including a lubricant cylinder having an inlet, a ram for ejecting lubricant from said cylinder, a pneumatic hammer arranged to drive said ram through its lubricant-ejecting stroke, said hammer comprising a pneumatic cylinder, a ram-impelling plunger in said pneumatic cylinder, an inlet passage for delivering compressed air into said pneumatic cylinder to the rear of said plunger for impelling the plunger into ram-driving position, an outlet passage for releasing air from said pneumatic cylinder to the rear of said plunger, a pneumatically operated air valve movable between alternate passage-controlling positions, and passages for supplying air at super-atmospheric pressure to said valve for shifting the valve between such positions.

8. Apparatus of the class described including a lubricant cylinder and a ram for forcing lubricant from such cylinder, a pneumatic hammer for driving said ram through its lubricant-ejecting stroke, a piston movable in a pneumatic cylin-

der for returning said ram from the end to the start of such stroke, passages leading from a supply of compressed air to said pneumatic hammer and said pneumatic cylinder, a valve controlled by said ram and movable between a position in which the passage to said hammer is blanked and the passage to the piston-including cylinder is open and a position in which the passage to the hammer is open and that to the piston-including cylinder is blanked.

9. In apparatus of the class described including a lubricant cylinder and a ram for forcing lubricant from such cylinder, a pneumatic hammer for driving said ram through its lubricant-ejecting stroke, a piston movable in a pneumatic cylinder for returning said ram from the end to the start of such stroke, a passage for compressed air leading to said pneumatic hammer, an exhaust passage opening from said pneumatic hammer to the outer atmosphere, a valve movable between a position in which said compressed air passage is open and said exhaust passage is closed and a position in which said exhaust passage is open and said compressed air passage is closed, and a passage for compressed air leading to said pneumatic piston-including cylinder, and a valve controlling the last-mentioned passage.

10. An apparatus of the class described comprising a cylinder that provides a container for a charge of lubricant, an outlet opening from said cylinder, a ram, a pneumatic hammer, a trigger controlling the delivery of compressed air to said hammer, said pneumatic hammer including a hammer element adapted to reciprocate continuously, when said trigger is in air-delivering position, to drive said ram through a lubricant-delivering stroke in said cylinder, means including a pneumatic valve for automatically arresting operation of said hammer element when, with the trigger still in air-delivering position, said ram reaches the end of its lubricant-delivering stroke, and means for automatically returning said ram to the beginning of its range of reciprocation while the operation of said hammer element is so arrested.

11. A grease gun including a lubricant cylinder with an outlet, a ram movable in such cylinder between lubricant-receiving position and lubricant-delivering position, and a pneumatic hammer adapted with repeated blows to drive said ram through its lubricant-delivering stroke in said cylinder, a passage for hammer-motivating compressed air leading to said pneumatic hammer, and means for automatically arresting the operation of the hammer when the ram reaches the end of said lubricant-delivering stroke, said means including a valve in said air passage and a portion carried by said ram and arranged to engage the valve and shift it into air-passage-blanking position when the ram reaches said end of its stroke.

12. A grease gun including a lubricant cylinder with an outlet, a ram movable in such cylinder between lubricant-receiving position and lubricant-delivering position, and a pneumatic hammer adapted with repeated blows to drive said ram through its lubricant-delivering stroke in said cylinder, a passage for hammer-motivating compressed air leading to said pneumatic hammer, and means for automatically arresting the operation of the hammer when the ram reaches the end of said lubricant-delivering stroke, said means including a valve in said air passage and a portion carried by said ram and arranged to engage the valve and shift it into

air-passage-blanking position when the ram reaches said end of its stroke, and pneumatic means for returning said ram from the end to the beginning of its stroke while the reciprocation of the hammer is so arrested.

13. A grease gun including a lubricant cylinder with an outlet, a ram movable in such cylinder between lubricant-receiving position and lubricant-delivering position, and a pneumatic hammer adapted with repeated blows to drive said ram through its lubricant-delivering stroke in said cylinder, a passage for hammer-motivating compressed air leading to said pneumatic hammer, and means for automatically arresting the operation of the hammer when the ram reaches the end of said lubricant-delivering stroke, said means including a valve in said air passage and a portion carried by said ram and arranged to engage the valve and shift it into air-passage-blanking position when the ram reaches said end of its stroke, and pneumatic means for returning said ram from the end to the beginning of its stroke while the reciprocation of the hammer is so arrested, said last

means including a device for effecting retardation of ram movement in said return stroke.

14. A grease gun including a lubricant cylinder with an outlet, a ram movable in such cylinder between lubricant-receiving position and lubricant-delivering position, and a pneumatic hammer adapted with repeated blows to drive said ram through its lubricant-delivering stroke in said cylinder, a passage for hammer-motivating compressed air leading to said pneumatic hammer, and means for automatically arresting the operation of the hammer when the ram reaches the end of said lubricant-delivering stroke, said means including a valve in said air passage and a portion carried by said ram and arranged to engage the valve and shift it into air-passage-blanking position when the ram reaches said end of its stroke, said ram carrying a second valve-engaging portion adapted, as the ram approaches the end of its return movement, to engage and shift said valve into its original position in which said air passage is open, with the effect that the arrested hammer is again set in operation.

WILLIAM L. OSTENDORF.
